Stephen Marsh of Torice Vermont

Letters Patent (Patented January 11. 1836.)

The Schedule referred to in these Letters Patent and making part of the same containing a description in the words of the said Stephen Marsh himself of his improvement in the complete Apparatus for Mapping, etc.

To all persons to whom these presents shall come Greeting. Be it known that of Stephen Marsh of Torice in the County of Chittenden and State of Vermont have Invented, constructed and applied to use a new and useful improvement in the mode and manner of Mapping and dressing cloth by one continuous operation until the mapping and dressing is completed which is known and denominated the complete Mapper: which said improvement is described and specified in the words and figures following, to wit: Figures one and two represent the two ends with all the frame work and machinery seen in those directions. And figures three and four represent the two sides of the frame and machinery as seen in those directions. The drawing is about one twelfth part of the size which is found to be suitable in practice, but may be taken in size to suit the operator. Figure 3. exhibits the cloth cylinders 13. The pulley 10. on one end and the friction bands to produce suitable tension on the cloth. The pulley which at the other end of the cloth cylinders are to go into a special cylinder or sleeve a section of which is seen at 12. & 13. are the adjusting cylinders and are connected by their pivots with the inner posts. Figure 4. Exhibits the mapping cylinder 15. the roller 16. The pulley called the driver pulley No 1. on the other end of the sleeve shaft to this is connected by a band with and carries pulley No 2. This pulley is a long one and carries the bands running from thence to pulleys 3, 4, 7, 8.

12.

The pulley 9. is fast on the shaft of the napping cylinder 15. and the pulleys 11, 8, 5 are loose. When the napping cylinder is required to go one way the open band is placed on pulley 9. and when it is required to go the other way the open band is slipped on to a loose pulley, and the cross band slipped on to pulley 8. On the same shaft of pulley of 1. is a loose pulley 6. freely set above pulley 7. to which it is connected by a band and on the same shaft, with pulley 7. is a small pulley 8. which is connected by a band with pulley 9. and on the inside of pulley 9 and concentric therewith is a small wheel attached to the said pulley, and turning therewith on an axis of rotation. The other small wheel connected with the above is on the shaft of the screw or spiral cylinder 12 in the end of which is a small shoulder or pivot which passes through the said axis of rotation and thereby keeps both wheels in due proximity.

Figure 1 exhibits an end view of the frame to which the machinery is attached and a side view of pulleys No 1, 7, 4 & 20, and an end view of the two cloth cylinders No 13. also the adjusting cylinder 11, attached by their posts to the inner posts, and the napping cylinder 15; also the lever 17 which is attached to the end of the roller 16. There is turned into the roller 12 upright No 18 connected by scroll joints with the inner posts by long tenons or second pieces. The cloth being stretched over the adjusting cylinder will then the cloth line, as marked from A to B. Then by raising the lever 17 will bring the cloth in contact with the napping cylinder 15. and by lowering the said lever will make the cloth recede from the said cylinder. For the purpose of holding the lever in its proper place a number of holes are bored in the post, into which an adjusting pin may be put and secured as occasion may require. On an adjusting cord or strap answers the same purpose. One pulley 9 is above the bevel gear above described attached to the screw or spiral cylinder as aforesaid. Figure 2 exhibits the opposite end of the frame from figure 1. and also a side view of pulleys No 1, 2, 3, 7, 8, and 9. and also a view of the spur wheels 10, on ends of the cloth cylinders, and the screw or spiral cylinder passing below them, and to be turned into either as occasion may require. Also an

view of the napping cylinder 15, and one of the adjusting cylinders 14. The dark parts of the napping cylinders are those on which the cards, or other napping material is fixed. The edges of the cards should be let into the cylinders nearly one eighth of an inch, so as to leave the card convex in the middle. The teeth of the card should radiate nearly in right lines from the center of the cylinder, or have but a small inclination or slope. To put this machine in operation first wind the cloth on the lower cloth cylinder, which may be done by a cord temporarily attached to the end of the gudgeon. Then bring the other end of the cloth around the adjusting cylinders and attach it to the upper cloth cylinder. Then gear the screw into the upper spur wheel, until the cloth has run on that cylinder, and so alternately until the nap is finished.

The back of the cards, or that way which will take the least hold of the cloth should be first used until the cloth is well napped, and then by changing from the open to the cropp band, run the napping cylinder the other way. This will keep the teeth of the cards always in order, and the cloth will not be injured. The said Stephen Marsh is aware that fullid bands, spur wheels, bavel wheels, plain napping, and spiral cylinders have been in use in various combinations, and hereby fully devolains all right or title to the inventions of any part of the complete napper, except what he truly believes is of his own invention, either in construction, combination or arrangement.

The said Stephen Marsh is not however aware that such a combination and arrangement of the different parts has heretofore been produced, nor is he aware that the teeth of the cards have been set at any other than the actual angle which from examination appears to be about 18° , nor is he aware that the tooth of one bavel or other wheel, has in any case been made to pass through the axis of rotation of its accompanying or connecting wheel.

The said Stephen Marsh therefore claims as his invention the invention of the card teeth, radiating in direct lines from the center, or a part of the cylinders, or having a less inclination than those which are now or heretofore have been in use. Also the passing of the tooth of one wheel through the axis of rotation of the other and the general arrangement and combination of the machinery as herein before set forth. In testimony that the foregoing is a
